ELECTRIC DISCHARGE TUBE

Guy Rabuteau, Paris, France, assignor to International Standard Electric Corporation, New York, N. Y.

Application November 11, 1936, Serial No. 110,256
In France December 12, 1935

12 Claims. (CL 250—27.5)

The present invention relates to improvements in means of support for electrodes of vacuum tubes or the like.

The invention particularly relates to means for supporting electrodes the relative position of which must be fixed to within close limits and has for an object to provide a simple and improved form of mounting for such electrodes.

In accordance with one feature of the invention, one at least of the electrodes of a vacuum tube or the like forms a unitary structure with a member adapted to be mounted by screwing, interlocking, or otherwise on an electrode support which preferably also forms a current conductor and the position of which may be strictly fixed during manufacture. The electrode support may for example be maintained rigidly in position by a tool engaged in the screwing or interlocking device provided in said support while it is being fixed permanently to the tube; preferably the axis of the electrode support forms an angle, for example an angle of 90° with the axis of the corresponding electrode.

The arrangement is particularly applicable in the case of tubes with coaxial electrodes. It is moreover especially useful in tubes for short or ultra-short waves where a small inter-electrode capacity is desired because the electrode support may be used as a current lead as already mentioned and the axis of this current lead may be different from that of the vacuum tube.

An electrode may according to the invention be provided with one or several supports and where several supports are employed they may be arranged for example as arms radiating round the axis of the tube; the axis of one or more of these arms may be inclined with respect to the axis of the tube and the arms may be placed on one side or on either side of the electrode.

The supports may be resilient or may be otherwise arranged to prevent undue stress upon the walls of the tube.

The above and other features of the invention will be better understood from the following description of an embodiment illustrated in the attached drawing in which:

Fig. 1 represents in elevation and in section a vacuum tube employing features of the invention;

Fig. 2 represents a view of the electrode supporting member;

Fig. 3 represents a sectional view of the same member.

Fig. 4 is an enlarged sectional view of the left hand portion of the structure of Fig. 1; and

Fig. 5 is a sectional view taken along section line 5—5 of Fig. 4.

Fig. 1 shows an anode 1 on which is fused at 3 a sheath of vitreous material 2. Inside the envelope formed by anode 1 and sheath 2 are provided (1) a filament 4 with its current leads 5 and 6 sealed in the vitreous sheath 2 at a filament foot 7; (2) a grid 8 placed inside the anode 1 around the filament 4 and supported by three leads 9, one of which is shown in Fig. 1. These leads are interconnected by rings 10 and 11. The grid wire 12 is fixed on the grid rods 9 in the usual way, by means of a lacing 13, for example.

The whole of the grid is carried by a tubular electrode support 14 fixed in the side wall of the sheath 2. The electrode support 14 is itself supported by a metal member or bushing 15 fused at 16 to the sheath 2.

The grid supporting rods 9 are fixed to the electrode support 14 by means of a plug member 17 which is screwed at 18 to the support 14. The whole grid structure constituted by the member 17, the rods 9, the rings 10 and 11, and the grid wire 12 has such dimensions that it can pass through the hole in the support 14. Thus the grid may be set in place and then fixed by screwing the member 17 into the support 14, as shown at 18 in Fig. 1.

A locking screw 19 may be screwed at 20 or 21 into the support 14, Fig. 2, in order to lock the member 17 and to prevent it from becoming unscrewed under the influence of vibrations or during the manufacture of the tube.

The support 14 is bored out along its axis at 22 and laterally at 23, 23' in order to reduce its weight and to permit evacuation of air inside the cavity 22. The support 14 is joined to the member 15 and to a disc or block 25, at 24 the three members 25, 14 and 15 being interconnected by the brazing 26. The end of the support 14 inside the joint is arranged so that a joint between the copper members 15 and 25 is directly formed by means of the brazing 26, the end of the support 14 being recessed by 1 mm. for example, with respect to the ends of the members 15 and 25 as shown at 25a.

It may be noted that in the embodiment shown in Figs. 1—3, the rod 14 serves at the same time as a grid supporting member and as a leading-in conductor for the grid.

The fixing of the grid structure by means of the member 17 screwing at 18 into the support 14 may be replaced by any other method of fixing, such as a bayonet joint, in which one or more fingers are engaged in ramps provided for

this purpose in the support 14. Such alternative couplings may be provided with locking systems such as that represented by the screw 19 in Fig. 1, or by any other suitable locking device.

5 The supporting arrangement shown in Fig. 1 may be applied to several concentric or other grids or electrodes arranged to pass during mounting through the central hole 27 of the support 14.

10 The support 14 represented in Fig. 2, may instead of being in a single piece be composed of two pieces, the cylindrical portion being screwed or fixed by other means such as soldering or locking in the ring portion bearing the thread 18.

15 One of the advantages of the arrangement of Fig. 1 is that it facilitates the centering of the electrodes of the tube in particular the centering of the grid to the other electrodes; the placing of the support 14 in the sheath 2 of the 20 anode 1 may be effected by means of a tool screwing in the thread 18, which tool is centered in such a way that the axis of the thread 18 exactly coincides with the axis of the anode 1 during the 25 fixing the member 14 for example by soldering at 26 as shown in Fig. 1. The tool is subsequently removed from the tube and the grid is set in place by passing it through the hole 27 and screwing the member 17 in the member 14 in the threads 18.

30 The grid having been made coaxial with the axis of the threads 18 of the member 17 becomes coaxial with the anode 1. In order to facilitate the centering of the grid a hole 1' may be provided in the anode 1, this hole being subsequently 35 blocked up in a suitable manner.

When several arms are provided for the grid support, these arms need not necessarily be rectilinear and may be curved so that the thread 18 is in a different plane from that of the arms of the support 14.

40 The invention is not limited to the embodiment described, for example, radiating arms serving as supports and preferably as current-leads to the electrodes may be arranged in different planes, for example, in parallel planes. In the same way at least one of the supporting members of an electrode may be composed of telescopic tubes mounted with sufficient friction to permit extension without looseness or other 45 harmful effects. Finally the device described may be applied not only to power tubes of the type with one or two bulbs but also to entirely metal tubes and to low power tubes such as receiving tubes.

50 What is claimed is:

1. An electrical discharge tube comprising in combination an envelope, an apertured supporting member fixed therein, an electrode structure, and coupling means including a plug portion fixedly positioned within the aperture of said supporting member for fixing said electrode structure to said supporting member.

60 2. An electric discharge tube comprising in combination an envelope, an aperture supporting member fixed therein, an electrode structure and a coupling member screw threaded in said aperture and a rod fixing said electrode structure to said coupling member.

65 3. An electric discharge tube comprising in combination a cylindrical envelope, a radial arm fixed therein, an axial socket in the radial arm, an axial electrode structure and a member attached thereto engaging said axial socket.

4. An electric discharge tube comprising in combination an envelope, a ring mounted intermediate the sides of the envelope, a bushing inserted in said ring and an electrode structure attached to said bushing and supported solely 5 thereby.

5. Method of assembling an electrode structure and a supporting arm having an opening therein within a vacuum tube consisting in fixing the supporting arm to the tube in predetermined relation thereto, passing said electrode structure through said opening in the supporting arm and securing said electrode structure at one end thereof to the supporting arm. 10

6. An electric discharge tube comprising in 15 combination an envelope, a plurality of electrodes therein, an electrode support fixed in predetermined relation to one electrode, an intermediate supporting member for another electrode and a 20 plug and socket coupling between said electrode support and said intermediate supporting member.

7. An electric discharge tube comprising in combination an envelope, a plurality of coaxial electrodes, a supporting arm fixed to the envelope 25 at an angle to the axis of the electrodes, an intermediate supporting member for an electrode and telescoping coupling means between said supporting arm and said intermediate supporting member retaining said intermediate supporting 30 member parallel to the axis of the electrodes.

8. An electric discharge tube comprising in combination an envelope, a plurality of coaxial electrodes, a supporting arm fixed to the envelope 35 at an angle to the axis of the electrodes, an axial aperture in said supporting arm and an axially arranged intermediate supporting member forming a unitary structure with one of said electrodes and having one end inserted and fixed in said axial aperture.

40 9. An electric discharge tube comprising in combination a cylindrical envelope, a plurality of electrodes coaxially disposed about the axis of said envelope, at least one radial supporting arm fixed in the envelope, a plurality of intermediate supporting members parallel to the axis and forming a unitary structure with one of said electrodes and preformed coupling means between said radial supporting arm and said intermediate supporting members. 45

10. A vacuum tube comprising in combination a cylindrical anode, a vitreous chamber forming with the anode a sealed envelope, a cylindrical grid structure within said anode and coaxial therewith, a grid supporting arm fixed in predetermined position in the vitreous chamber, an aperture in said grid-supporting arm and means inserted in said aperture and carrying said grid structure. 50

11. A vacuum tube according to claim 1 said electrode structure having a diameter smaller than the aperture diameter so that it may be passed through said aperture. 60

12. In combination in a vacuum tube, a glass envelope, a metal support having a tubular stem extending through said envelope and closed at its outer end by a disc, a member encircling said stem and having a flange fused to the said envelope around the said stem and metallic means joining said disc to said member. 65
